No. 756,962.

PATENTED APR. 12, 1904.

W. N. HOOPER & T. J. SUNDAY.

RAILROAD JOINT AND CHAIR.

APPLICATION FILED MAY 21, 1903.

NO MODEL.

UNITED STATES PATENT OFFICE.

WILLIAM N. HOOPER AND THOMAS J. SUNDAY, OF CONROE, TEXAS.

RAILROAD JOINT AND CHAIR.

SPECIFICATION forming part of Letters Patent No. 756,962, dated April 12, 1904.

Application filed May 21, 1903. Serial No. 158,171. (No model.)

To all whom it may concern:

Be it known that we, WILLIAM N. HOOPER and THOMAS J. SUNDAY, citizens of the United States, residing at Conroe, in the county of 5 Montgomery and State of Texas, have invented a new and useful Railroad Joint and Chair, of which the following is a specification.

This invention relates to improvements in the joints for uniting railway-rails, and has 10 for its object to simplify and improve devices of this character and to produce a device which may be cheaply constructed, easily applied, and which will rigidly support the rails and effectually prevent deflection or "creeping" 15 thereof.

The invention consists in certain novel features of construction, as hereinafter shown and described, and specified in the claims.

In the drawings illustrative of the invention, in which corresponding parts are denoted 20 by like designating characters, Figure 1 is a side elevation. Fig. 2 is a transverse section on the line 2 2 of Fig. 1. Fig. 3 is a perspective view of the improved chair detached.

The device may be adapted to any form or 25 size of rail, and consists of a chair with its lower side 10 extending beneath the abutting ends of the rails 11 12 and with the sides 13 14 extending into engagement with the opposite tie-flanges and vertical webs of the rails, as shown, the side 14, which engages the outer 30 sides of the rails, being extended to a point relatively near the upper faces of the treads or "heads" of the rails, with the ends thereof inclined downward to guide the rails thereinto in their passage thereover, while the other side will be sufficiently low to prevent interference with the flanges of the passing wheels. The sides 13 14 will be provided with trans-

40 verse apertures spaced apart and registering with corresponding apertures in the vertical webs of the rails to receive the transverse clamp-bolts 15, as shown. The apertures in the side 14 are preferably square, and the 45 bolts 15 at their head ends will be correspondingly square, as indicated in Fig. 2, so that the nuts (represented at 16) will not be liable to work loose.

The ends of the chair extend over the adjacent ties 17 18, and between the ties the chair

is reinforced by increasing the thickness of the portion 10, as at 19, with shoulders 20 21 adapted to embrace the adjacent inner faces of the ties. At their ends the sides 13 14 are curved inwardly, whereby flanges 22 23 are 55 formed to receive spike-apertures, by which the chair may be connected to the ties. By this means the spikes hold the chair firmly to the ties and prevent vertical and lateral displacement, while the depending portion 19, together with its shoulders 20 21, coacting with the spikes, effectually prevent longitudinal movement or the creeping movement of the rails. By this simple means a very rigid solid support is produced which will firmly support 60 the rail ends and effectually prevent movement in any direction.

The chair will preferably be of cast-steel and may be of any size and adapted to any size or form of rail.

The apertures for the bolts 15 through the vertical webs of the rails will be elongated in the usual manner to provide for the contraction and expansion.

Having thus described the invention, what 75 we claim is—

1. A railway-rail joint comprising a chair adapted to support the abutting rail ends and with extended sides for engagement with the opposite base-flanges of the rails and having 80 transverse spaced apertures, the apertures of one side being angular the chair having central reinforcing portions provided with shoulders for engagement with the adjacent faces of the ties, and clamp-bolts engaging said 85 transverse apertures, and having one end thereof made angular to fit said angular apertures.

2. A railway-rail joint comprising a chair adapted to support the abutting rail ends and 90 with extended sides for engagement with the opposite base-flanges of the rails and having transverse spaced apertures, the chair having central reinforcing portions provided with shoulders for engagement with the adjacent 95 faces of the ties, the outer faces of said sides being flush with the lower edges of the chair, and with the ends of said extended sides curving inwardly to provide flanges to receive fastening-spikes.

3. A railway-rail joint comprising a chair adapted to support the abutting rail ends and with extended sides for engagement with the opposite base-flanges of the rails, one of said sides extending to a point relatively near the upper face of the tread of the rail, and having the tread thereof curved downwardly at its opposite ends to guide the wheels thereonto in their passage thereover.

In testimony that we claim the foregoing as ¹⁰ our own we have hereto affixed our signatures in the presence of two witnesses.

WILLIAM N. HOOPER.
THOMAS J. SUNDAY.
